COLLAPSIBLE DISPLAY DEVICE

William Dale Rudy, Hoboken, N. J., assignor to
 Arvey Corporation, Chicago, Ill., a corporation
 of Illinois

Application June 27, 1945, Serial No. 601,886

7 Claims. (Cl. 211—74)

This invention relates to improvements in collapsible display devices, and has for an object the provision of a device of this kind adapted to be formed of a single sheet of cardboard suitably cut and scored to form a central display panel, a central platform, and angularly disposed side panels and side platforms, said side panels being foldable inwardly against the front face of the center panel to collapse the central and side platforms and thus provide a relatively flat, compact display suitable for shipping or storage.

It is a further object of this invention to provide a collapsible, platform type display device which may readily be extended for display purposes by merely swinging the side panels outwardly to their extended positions. During the outward movement of the side panels, the central platform and side platforms are drawn into their horizontal supporting positions at right angles to their respective panels.

It is a further object of this invention to provide a platform display of this type in which means are provided for supporting the central and side platforms in their extended positions, said supporting means being automatically moved into supporting position during outward, unfolding movement of the side panels.

This invention further contemplates the provision of a platform type display device in which the sheet material may be cut and scored to provide an upper platform extending outwardly at right angles from the central panel and above the center platform.

A further object of this invention is to provide a collapsible, platform type display device which may be provided with an upper display panel pivotally connected to the upper edge of the central display panel, and a collapsible easel secured to the back side of the central panel for supporting the pivotally connected central panel in upright position.

This invention embodies other novel features, details of construction and arrangement of parts which are hereinafter set forth in the specification and claims, and illustrated in the accompanying drawings wherein:

Fig. 1 is a front elevational view showing a collapsible, platform type display device embodying features of this invention, said device being shown in its extended position.

Fig. 2 is a plan view of same.

Fig. 3 is a sectional view taken along the line 3—3 of Fig. 1.

Fig. 4 is a sectional view taken along the line 4—4 of Fig. 1.

Fig. 5 is a plan view showing a sheet of cardboard or the like cut and scored to form the collapsible display device.

Referring now to the drawings for a better understanding of this invention, a collapsible display is shown as comprising a sheet of cardboard 8, or other suitable material, adapted to be cut and scored to form several pivotally connected portions adapted to be folded or unfolded without breaking the hinge connections provided by the score lines. The display preferably comprises a central display panel 9 having side panels 11 pivotally connected thereto by means of vertically disposed score lines 12 formed on the back side of the blank 8. A central platform 13 is pivotally connected to the central panel 9 by means of score lines 14 formed on the back side of the blank, and side platforms 16 are hinged to the side panels 11 by means of score lines 17 which are also formed on the back side of the blank and extend in alignment with the score lines 14. Risers 18 and 19 are hinged to the platforms 13 and 16, respectively, by means of score lines 21 and 22, respectively, formed on the front face of the blank 18 and extending parallel to the score lines 14 and 17.

It will be noted that the risers 18 and 19 are coextensive in height and serve to support the forward edges of their respective platforms 13 and 16. A pair of apertures 23 in the form of isosceles triangles are formed in the blank 8 between the center platform 13 and side platforms 16, and having their bases disposed in alignment with score lines 21 and 22 and their apices disposed at the juncture of score lines 12, 14 and 17. The blank 8 is cut vertically at 24, said cuts extending in vertical alignment with the score lines 12 to provide flaps 27 and 28 on adjacent ends of the riser portions 18 and 19.

It will be noted that the angular relation of the side panels 11 with the central panel 9 is determined by the angle between the sides of the triangular apertures 23 defined by the adjacent edges of the platform portions 13 and 16, said edges being secured in abutting engagement by means of glue or staples 26 securing the flaps 27 and 28. In applying the staples 26, the side panels 11, side platforms 16 and side risers 19 are first folded inwardly for flat engagement against the face of the blank. The staples are then applied to engage the flap portions 27 and 28 of the risers 18 and 19, respectively, as indicated in Figs. 2 and 5 of the drawings.

It will be noted that the side risers 19 may be pivotally connected to the central riser 18 by means of score lines in place of the cuts 24 to provide connected flap portions 27 and 28 adapted to be disposed in face to face relation and connected together by means of glue or staples 26.

A base portion 29 is pivotally connected to the lower edge of the central riser 18 by means of a score line 31 formed on the front face of the blank 8. A back riser 32 is preferably pivotally connected to the base portion 29 by means of a score line 33 formed across the front face of the blank, although it is contemplated that the back riser may be formed as a separate piece and fastened by means of glue or staples to the base portion 29 and to the back side of the central panel 9 of the blank. The back riser 32 is adapted to engage the back side of the central panel 9 and to be adhesively united therewith in the position indicated in Fig. 3.

If desired, an upper platform 34 may be provided above the central platform 13 by means of spaced parallel cuts 36 and 37 extending vertically from the score lines 21 defining the forward edge of the platform 13. Transverse score lines 38 and 39 extend between cuts 36 and 31 and are spaced apart equal to the spacing between the score lines 14 and 21 to provide an upper platform coextensive in width with the platform 13.

An easel 41 formed of cardboard is provided with a score line to provide a leg portion 42 for adhesive engagement with the back surface of the back riser 32 and a leg 43 to project rearwardly at right angles to the leg 42. A suitable locking flap 44 is provided on the easel for detachable engagement with the leg 43 to hold same in its rearwardly extending position. If desired, the upper portion 9a of the central panel 9 may be pivotally connected thereto by means of a score line 46 formed in the front face of the blank, in which event a score line 47 is provided to extend transversely across the legs 42 and 43 of the easel in order that the upper portion of the legs may be folded downwardly for flat surface engagement against the lower portions of the legs.

In the use of a collapsible display of the type described, it will be noted that the several movable portions thereof may be moved from the flat collapsed positions to their extended positions by merely engaging the free ends of the side panels 11 and moving same outwardly to their extended positions indicated in Fig. 2. Outward movement of the side panels 11 causes the blank portions 13, 16, 18, 19 and 34 to assume the positions indicated in Fig. 3 to provide a central platform 13 and an upper platform 34. When the several parts of the display device have been moved to their extended positions, it will be noted that the flap portions 27 and 28 are disposed under the side platforms 16 to serve as supports for same.

The easel 41 serves to hold the display in an upright position and to prevent collapse of same. The easel 41 is opened by moving the upper ends of the legs 42 and 43 upwardly about the score line 47, then moving the leg 43 at right angles to the leg 42, and then moving the locking flap 44 into engagement with the leg 43.

It will thus be seen that an easel constructed in the manner thus shown and described is relatively inexpensive to manufacture, may readily be folded for shipping or storage, and may readily be extended to provide a sturdy and attractive display device for various types of merchandise.

While this invention has been shown in but one form, it is obvious to those skilled in the art that

it is not so limited but is susceptible of various changes and modifications without departing from the spirit and scope of the claimed invention.

5 I claim as my invention:

1. In a collapsible display device formed of sheet material cut and scored to provide a central panel, side panels hinged to the sides of the central panel, a central platform hinged to the lower edge of the central panel, side platforms hinged to the lower edges of the side panels, a central riser hinged to the forward edge of the central platform, side risers hinged to the forward edges of the side platforms, tab portions 10 formed on adjacent ends of said risers, means for securing said tab portions together in face to face relation, said side panels, platforms and risers being foldable into the plane of the central panel and extendable by outward pivotal movement of 15 said side panels, said tab portions being disposed to support said side platforms when the display device is in its extended position.

2. In a collapsible display device formed of a sheet having a plurality of spaced parallel score lines extending longitudinally and transversely to provide foldable portions comprising, laterally disposed vertical display panels, platform portions pivotally connected to the lower edges of their respective display panels for angular displacement from the plane of said panels, riser portions pivotally connected to the forward edges of said platform portions for movement from the plane of said display panels, said platform portions having their adjacent edges diverging outwardly from the pivotal connection of adjacent display panels, and means for securing adjacent ends of said riser portions together to hold the edges of adjacent platform portions in abutting relation when the display is in its extended position.

3. In a collapsible display device formed of a sheet having a plurality of spaced parallel score lines extending longitudinally and transversely to provide foldable portions comprising, laterally disposed vertical display panels, platform portions pivotally connected to the lower edges of their respective display panels for angular displacement from the plane of said panels, riser portions pivotally connected to the forward edges of said platform portions for movement from the plane of said display panels, said platform portions having their adjacent edges diverging outwardly from the pivotal connection of adjacent display panels, and staple means for securing adjacent ends of said riser portions together in face to face relation to hold the edges of adjacent platform portions in abutting relation when the display is in its extended position.

4. In a collapsible display device formed of a sheet having a plurality of spaced parallel score lines extending longitudinally and transversely to provide foldable portions comprising, laterally disposed vertical display panels, platform portions pivotally connected to the lower edges of their respective display panels for angular displacement from the plane of said panels, riser portions pivotally connected to the forward edges of said platform portions for movement from the plane of said display panels, said platform portions having their adjacent edges diverging outwardly from the pivotal connection of adjacent display panels, and staple means for securing adjacent ends of said riser portions together in face to face relation to hold the edges of adjacent platform portions in abutting relation when the display is in

its extended position, the ends of said riser portions being formed to support adjacent platform portions when same are in extended position.

5. In a collapsible display device formed of a sheet having a plurality of spaced parallel score lines extending longitudinally and transversely to provide foldable portions comprising, laterally disposed vertical display panels, platform portions pivotally connected to the lower edges of their respective display panels for angular displacement from the plane of said panels, riser portions pivotally connected to the forward edges of said platform portions for movement from the plane of said display panels, said platform portions having their adjacent edges diverging outwardly from the pivotal connection of adjacent display panels, and staple means for securing adjacent ends of said riser portions together in face to face relation to hold the edges of adjacent platform portions in abutting relation when the display is in its extended position, the ends of said riser portions being formed to support adjacent platform portions when said platform portions are in extended position, a base portion hinged to the lower edge of a riser portion, a back riser portion hinged to said

staple means for securing adjacent ends of said riser portions together in face to face relation to hold the edges of adjacent platform portions in abutting relation when the display is in its extended position, the ends of said riser portions being formed to support adjacent platform portions when said platform portions are in extended position, a base portion hinged to the lower edge of a riser portion, a back riser portion hinged to said 5 base portion for engagement to the back side of a display panel portion, and an upper platform portion hinged at its inner end to one of said vertical display panels and hinged at its outer end to the adjacent riser portion and defined by a 10 pair of spaced vertically disposed cuts and a pair of transversely extending score lines.

15 7. In a collapsible display device formed of a sheet having a plurality of spaced parallel score lines extending longitudinally and transversely to provide foldable portions comprising, laterally disposed vertical display panels, platform portions pivotally connected to the lower edges of their respective display panels for angular displacement from the plane of said panels, riser portions pivotally connected to the forward edges of said platform portions for movement from the plane of said display panels, said sheet being cut away 20 to form triangular apertures between adjacent ends of said platform portions, said apertures having their apices at the intersection of the score lines defining said display panels and platform portions, said apertures having their bases in alignment with the pivotal connection between said panel and riser portions, and means for securing adjacent ends of said riser portions together to hold the edges of adjacent platform portions in abutting relation when the display 25 is in its extended position.

6. In a collapsible display device formed of a sheet having a plurality of spaced parallel score lines extending longitudinally and transversely to provide foldable portions comprising, laterally disposed vertical display panels, platform portions pivotally connected to the lower edges of their respective display panels for angular displacement from the plane of said panels, riser portions pivotally connected to the forward edges of said platform portions for movement from the plane of said display panels, said platform portions having their adjacent edges diverging outwardly from the pivotal connection of adjacent display panels, 40

WILLIAM DALE RUDY.
